(57) **CLAIM**

The ornamental design for a template, as shown and described.

DESCRIPTION

FIG. 1 is a bottom plan view of a template of the present invention.

FIG. 2 is an elevation view of the template viewed from the front of FIG. 1, the rear elevation view being a mirror image thereof.

FIG. 3 is a top plan view of the template shown in FIG. 1. FIG. 4 is a side elevation view of the template taken from the left side of FIG. 1; and,

FIG. 5 is a side elevation view of the template taken from the right side of FIG. 1.
